COMBINED SIGNAL LIGHT AND TOW HITCH FOR BOATS

Andrew George Griparis, 1000 Westminster Road,
Joliet, Ill.

Filed Aug. 18, 1960, Ser. No. 61,808

Term of patent 14 years

(Cl. D71—1)

FIG. 2

FIG. 1

FIG. 1 is a front perspective view of a combined signal light and tow hitch for boats showing my new design.

FIG. 2 is a rear perspective view thereof on an enlarged scale and with a portion broken away for convenience of illustration.

The side not shown is a mirror image of the side shown.

I claim:

The ornamental design for a combined signal light and tow hitch for boats, as shown and described.
